[57] CLAIM

The ornamental design for a reflector for warning light, as shown and described.

DESCRIPTION

FIG. 1 is a perspective view of a first embodiment of a reflector for warning light showing my new design;

FIG. 2 is a front elevation view of the reflector of FIG. 1; FIG. 3 is a side elevational view of the reflector of FIG. 1, the reflector appearing the same when viewed from the opposite side;

FIG. 4 is a bottom view of the reflector of FIG. 1, the reflector appearing the same when viewed from the top;

FIG. 5 is a perspective view of a second embodiment of a reflector for warning light showing my new design;

FIG. 6 is a front elevation view of the reflector of FIG. 5; FIG. 7 is a side elevation view of the reflector of FIG. 1, the reflector appearing the same when viewed from the opposite side; and,

FIG. 8 is a bottom view of the reflector of FIG. 5, the reflector appearing the same when viewed from the top.

The appearance of my new design as seen from the rear forms no part of the claimed design.
